UNITED STATES PATENT OFFICE.

JOHN THOMAS JOHNSON, OF KELLERTON, ASSIGNOR OF ONE-HALF TO
CALVIN B. MORRIS, OF MOUNT AYR, IOWA.

SCAFFOLDING-SUPPORT.

SPECIFICATION forming part of Letters Patent No. 352,873, dated November 16, 1886.

Application filed April 8, 1886. Serial No. 198,232. (No model.)

To all whom it may concern:

Be it known that I, JOHN THOMAS JOHNSON, of Kellerton, in the county of Ringgold and State of Iowa, have invented certain new and useful Improvements in Scaffolding-Supports; and I do hereby declare the following to be a full, clear, and exact description of the invention, such as will enable others skilled in the art to which it pertains to make and use the same.

My invention relates to scaffolding-supports adapted for the use of masons in building chimneys, the object being to provide a device of this character that may be applied without the use of nails, thus preventing leakages in the roof ordinarily caused by nail-holes.

My invention consists in the combination, with a pair of hinge-jointed main or straddle bars, of adjustable arms and braces secured to the outer sides of said main bars. My invention further consists in the various features of construction hereinafter fully described, and pointed out in the claim.

In using my improvements, two complete devices are necessary, but as they are similar in construction the following description of one will suffice for both.

In the drawings, Figure 1 represents the roof of a house with my improvements applied thereto; and Figs. 2 and 3 show parts in detail.

A A represent two bars of equal length hinge-jointed together at their inner ends.

B B represent two supporting-arms pivot-

ally secured to the sides of bars A A at some distance below their connection.

D D represent braces hinge-jointed to the supporting-arms B B at their extremities and provided at their lower ends with pins E E, adapted to enter perforations F in plates G, secured to the bars A A.

In using my improvements the operation is as follows: The bars are placed over the peak of the roof, and in consequence of their hinge connection they will conform to the angle of the roof. When they are in place the supporting-arms are adjusted by placing the pins at the ends of the braces, in the perforations that will give the desired adjustment, and after each supporting-arm is so adjusted a platform 45 that will permit workmen to work thereon may be made by any means desired.

Having fully described my invention, what I claim as new, and desire to secure by Letters Patent, is—

The combination, with two main bars hinge-jointed together and provided with perforated plates G, of hinged arms, and hinged braces D, provided with pins E, adapted to enter the perforations of the plates, substantially as described.

In testimony whereof I have signed this specification in the presence of two subscribing witnesses.

JOHN THOS. JOHNSON.
